FLATIRON

Filed Feb. 17, 1927

Inventor:
Charles Endorf
By: Arthur L. Sprinkle
Atty.

UNITED STATES PATENT OFFICE

CHARLES ENDORF, OF CHICAGO, ILLINOIS

FLATIRON

Application filed February 17, 1927. Serial No. 168,878.

This invention relates to flatirons and particularly to a novel construction and arrangement of means for protecting the hand of the user from the heat of the iron while in use.

5 One of the objects of the present invention is to provide a suitable shield between the handle and heating element of the iron, whereby the heat arising from said heating element will be deflected away from the 10 handle of the iron and the hand of the user.

Another object of the invention is to provide a construction and arrangement whereby the shield may be suitably ventilated in a manner to prevent the transmission of heat 15 through the shield to the handle.

A further object of the invention is to provide a construction whereby the area of contact between the handle and shield is reduced to a minimum, thereby further eliminating 20 to a considerable degree the possibility of heat transmission from the iron to the handle.

And a still further object of the invention is to provide an efficient heat deflecting shield which is cheap to manufacture and which 25 may be quickly and easily applied to a flatiron structure, and to improve devices of this character in sundry details hereinafter described and particularly pointed out in the appended claims.

30 One embodiment of the invention is shown for illustrative purposes in the accompanying drawing, in which—

Fig. 1 is a side elevation of an electric flatiron illustrating the application of my invention thereto.

Fig. 2 is a side elevational view, partly in section, showing the manner of assembling the various elements of the flatiron to which my invention is applied, and illustrating 40 more specifically the construction and arrangement of my improved protecting means.

Fig. 3 is a transverse sectional elevation through my improved ventilated heat deflecting shield taken as indicated by the line 3—3 45 in Fig. 2, and

Fig. 4 is an enlarged perspective view of my improved shield illustrating the manner of ventilating the same, and the means for spacing the handle therefrom.

50 In the illustrative embodiment of the

drawings, my invention is shown applied to an electrically heated flatiron comprising a base plate member 5, a pressure plate 6, and a handle or handle bracket 7 having upturned portions, between the outer ends of which is secured a grip 8 of suitable material such as wood or the like, or other material non-conductive of heat.

55 Interposed and rigidly secured between the pressure plate 6 and the handle 7 is my improved heat deflecting shield 9 shown, in the present instance, as of inverted cup-shaped formation having a body portion 10 and a downwardly extending serrated peripheral flange portion 11, provided with a plurality of spaced projections or teeth 12 forming interdental spaces or notches 13 along the edge of the flange.

60 In the construction shown, the base plate 5 is provided with a plurality of suitably positioned studs 14 screw threaded into the base plate as shown in Fig. 2, and adapted to extend upwardly through openings formed in the pressure plate 6, and to receive at their upper end portions, in screw-threaded engagement therewith, the nuts 15 for securing the base plate 5 and pressure plate 6 together.

65 The body portion 10 of the shield 9 is provided with suitably spaced openings 16 adapted to receive the studs 14, and also with a plurality of bosses 17 positioned preferably concentric with the openings 16, the bosses being shown, in the present instance, as formed by pressing the material of the shield 70 outwardly and upwardly from the body portion thereof, thus forming a plurality of recesses in the under or inner side of the shield for the reception of the nuts 15.

75 It will be noted that when the shield 9 is positioned on top of the pressure plate 6 with the studs extending through the opening 16, and the notched portion of the flange 11 positioned adjacent the plate 6, a cooling 80 chamber is formed between the shield and the plate 6, and a plurality of openings are formed by the interdental spaces 13 through 85 which the air may circulate and carry off the heat which would otherwise accumulate in 90

the said chamber and cause an excessive heating of the shield 9.

5 The handle 7 is provided with suitable openings adapted to receive the studs 14 and is positioned above the shield in a manner to rest on and be supported by the bosses 17, thereby having only two points of contact with the shield, the bosses 17 serving to space the handle from the body of the shield 10 in a manner to permit the circulation of air therebetween to prevent the transmission to the handle of any small amount of heat which the shield 9 may acquire.

Screw-threaded to the upper ends of the 15 studs 14 are nuts 18 by which the shield is securely clamped between the handle 7 and pressure plate 6 and by which the handle is rigidly secured in place.

It will be observed from the foregoing description that my invention provides an efficient heat deflecting shield for flatirons which is cheap to manufacture, quickly and easily applied, and which may be readily and thoroughly ventilated to prevent any appreciable transmission of heat therethrough. Furthermore, the invention provides a structure and arrangement whereby the area of contact between the shield and handle is reduced to a minimum and provides a ventilating space between these elements, thereby 30 further reducing the possibility of heat transmission to the handle of the flatiron.

Obviously, the present invention is not limited to the precise construction and arrangement shown and described, as the same may be variously modified without departing from the spirit and scope of the invention as set forth in the appended claims. Furthermore, all the features of the invention need 35 not be used conjointly, as the same may be used to advantage in variously different combinations and subcombinations.

What I claim as my invention and desire to secure by Letters Patent is:

45 1. In a flatiron, a base plate having a plurality of threaded studs mounted thereon, a pressure plate mounted on said base plate and having openings therein adapted to receive said studs, means co-operable with said studs and said pressure plate for securing 50 said plates together, a ventilating plate adapted to cover said securing means and having openings therein adapted to receive said studs, said ventilating plate being spaced 55 from said pressure plate and having a serrated marginal flange portion extending downwardly toward said pressure plate to engage the top of said pressure plate and form a chamber open to the circulation of 60 air between said ventilating plate and said pressure plate, a handle having openings adapted to receive said studs, a plurality of hollow bosses formed on said ventilating plate adjacent said studs and adapted to receive 65 said pressure plate securing means and

70 to space said handle from said ventilating plate, and means co-operable with said studs for securing said handle and ventilating plate to said pressure plate and said pressure plate securing means.

75 2. In a flat iron, a base plate having a plurality of threaded studs mounted thereon, a pressure plate mounted on said base plate, said pressure plate having openings therein adapted to receive said studs, means co-operable with said studs and said pressure plate for securing said base plate and said pressure plate together, a ventilating plate formed with a downwardly extending serrated outer periphery secured to the upper 80 surface of said pressure plate whereby to form a chamber with partially open side walls to permit the passage of air currents laterally and horizontally between said pressure plate and said ventilating plate, and to leave the side walls of said pressure plate uncovered, a handle bracket having openings 85 adapted to receive the upper ends of said threaded studs, and means co-operable with said studs for securing said handle above 90 said ventilating plate upon the upper ends of said studs.

95 3. In a flat iron, a base plate, a pressure plate mounted thereon, a plurality of studs screw threaded at their lower ends into said base plate, means on said studs comprising threaded nuts for locking said base plate and said pressure plate together, a ventilating plate formed with a downwardly extending serrated outer periphery adapted to overlie 100 the upper side of said pressure plate whereby to form a chamber with partially open side walls to permit the passage of air currents laterally and horizontally between said pressure plate and said ventilating plate, a handle bracket having openings to receive the upper ends of said threaded studs, and threaded nuts co-operable with the upper 105 ends of said studs to clamp said ventilating plate upon the aforesaid locking nuts on said studs.

110 In testimony whereof I have signed my name to this specification, on this 14th day of February, A. D. 1927.

CHARLES ENDORF.
